UNITED STATES PATENT OFFICE

140,364

DESIGN FOR FONT OF MUSIC TYPE

Jack C. Lewis, New York, N. Y.

Application November 13, 1942, Serial No. 108,764

Term of patent 3½ years

(Cl. D64—12)

To all whom it may concern:

Be it known that I, Jack C. Lewis, a citizen of the United States, residing at 444 East 52nd Street, city of New York, of the county of New York and State of New York, have invented a new, original, and ornamental Design for Font of Music Type, of which the following is a specification, reference being had to the accompanying drawing forming part thereof.

The drawing is a face view of font of music type showing my design.

I claim:

The ornamental design for font of music type, as shown.

JACK C. LEWIS.
